Des. 220,120
Patented Mar. 9, 1971

220,120

NAVIGATIONAL LIGHT

Donald E. Stewart, Grand Rapids, Mich., assignor to
Attwood Corporation, Lowell, Mich.

Filed Sept. 18, 1969, Ser. No. 19,203

Term of patent 14 years

Int. Cl. D12—99

U.S. Cl. D48—32

FIG. 1.

FIG. 2.

FIG. 3.

FIG. 4.

FIG. 5.

FIG. 6.

FIG. 7.

FIG. 8.

FIG. 1 is a perspective view of a navigational light showing my design, the design being embodied in a bow light.

FIG. 2 is a front elevational view thereof.

FIG. 3 is a rear elevational view thereof.

FIG. 4 is a side elevational view thereof.

FIG. 5 is a perspective view of a second embodiment of the navigational light, the design being embodied in a right side running light.

FIG. 6 is a side elevational view thereof.

FIG. 7 is a top plan view of the embodiment shown in FIG. 1.

FIG. 8 is a top plan view of the embodiment shown in FIG. 5.

FIG. 9 is a perspective view of a third embodiment of the navigational light, the design being embodied in a side running light.

FIG. 10 is a side elevational view thereof.

FIG. 11 is a top plan view thereof.

I claim:

The ornamental design for a navigational light, as shown and described.
